7 Claims. (Cl. 214—11)

This invention relates to the art of mechanical sorting, particularly to machines for sorting non-uniform articles within a given size parameter.

Although our invention is especially useful in sorting letters, it is to be understood that the principles of the invention apply to solve problems in sorting numerous different kinds of articles such as papers, rigid or flexible sheets or panels, packages, books, or magazines. For brevity, the subsequent description relates to letter sorting.

Prior sorting machines are reasonably satisfactory, however, they have difficulties which have been tolerated in the past, but which are overcome by the invention. For example, prior machines do not satisfactorily sort all letter mail, since some letter mail is often crumpled, torn, partially open, or otherwise mutilated, and it always varies in texture, size, weight, and general configuration. Further, current machines are large, bulky and expensive. Accordingly, an object of the invention is to provide a comparatively small, inexpensive letter sorting machine which functions more satisfactorily than prior machines in that our machine is capable of sorting almost any mail regardless of the condition of letters and regardless of the other variables relating to texture, thickness, reasonable mutilation, etc.

Briefly, a machine following the principles of the invention, has an article, e.g. letter, sorting structure preferably made of a number of spaced guides over which the article is moved. Letter diverting means such as a gate or number of gates, in or essentially constituting the supporting structure, are arranged to open and close, as programmed or coded, to do the actual sorting. Instead of moving the letters while they are in an upright position such as in U.S. Patent No. 2,901,089, the letters are moved flatwise through a constrained path so that no direction changing transformation space is required in the machine handling of the letters. This provides a bulk reducing advantage of our machine.

A feature of the invention is the means used to move the letters through the machine. Symmetrical, undulated rod-like members are interdigitated with the guides and sweep the letters, one by one, along the supporting structure which is usually horizontal except at the ends which are generally vertically curved. In the manifold configuration having superposed guide sections, the undulated shape is very important since it allows the undulated propelling member to remain in contact with a particular letter during the entire path of travel of the letter, especially as it moves from one section to another, and the same undulated member positively propels the letter into a final receptacle.

Another feature of the invention which leads to a simpler machine, is our gate operating mechanism. It is so constructed that the gates are actuated only when absolutely required, and then only for a half cycle. U.S. Patent No. 2,901,089, discloses a selective mechanism for unloading pockets in accordance with the comparative setting of code wheels and tracks. This invention improves the functional utility of this mechanism by adding a swingable arm which is translated with the undulated member discussed above. The arm has a cam follower which enters the special throat of a cam at each gate sta-

2

tion, the cam follower automatically detecting the position of the gate and if satisfactory, the gate is not moved. However, if the gate is in the incorrect position (which may be either open or closed) the cam follower causes the gate to move to the proper position where it remains until the next cam follower goes through the same procedure. This has the advantage of gate operation only on demand of the mechanical programming of the machine.

Accordingly, another object of the invention is to provide a machine incorporating one or more of the above features to reduce the bulk of high output, dependable sorting machines.

Other objects, features, and advantages of the invention will become evident in following the description of the illustrated embodiments of the invention.

FIGURE 1 is a diagrammatic side elevational view of a sorting machine embodying the principles of the invention.

FIGURE 2 is an enlarged cross-sectional view taken on the line 2—2 of FIGURE 1.

FIGURE 3 is a fragmentary top view showing essentially the same part of the machine which is illustrated in FIGURE 2.

FIGURE 4 is a largely diagrammatic view taken approximately on the line 4—4 of FIGURE 3 and showing gate operation.

FIGURE 5 is an enlarged sectional view taken on the line 5—5 of FIGURE 2 showing principally a mechanical device to hold the gate in an open or a closed position.

FIGURE 6 is an enlarged sectional view taken approximately on the line 6—6 of FIGURE 2 and showing the relationship of the coding device and a set of gate operating cams.

FIGURE 7 is a wholly schematic view showing the possible gate operating cam movements and further showing how the gate is moved only on demand.

FIGURE 8 is a fragmentary perspective view showing a set of cams which form a preferred means to operate the gates to the open or closed position.

FIGURE 9 is a fragmentary, diagrammatic side elevation view showing one possible way of connecting an upper and lower article guide structure section in order to form a continuous path for the movement of the articles.

FIGURE 10 is a side elevational view of one of the article propulsion members used in the preferred form of our machine.

FIGURE 11 is a side elevation view showing one module from which higher capacity machines may be constructed by stacking a number of such modules and making minor modifications as to the conveyor.

FIGURE 12 is a diagrammatic view showing a letter entering the machine.

In the accompanying drawings there is an illustration of a machine 10 capable of sorting numerous different types or classes of articles, and the machine embodies the principles of the invention. Although many different types of articles may be sorted by our machines and since the machine is ideally suited for sorting letter mail, the subsequent description relates only to this particular type of article.

FIGURES 1 and 11 are diagrammatic side elevational views and as such, machine 10 in FIGURE 1 discloses a suitable frame 12, while machine 10a in FIGURE 11 discloses a suitable frame 12a. Machine 10a is actually a module from which a machine such as that shown in FIGURE 1 may be constructed by vertically stacking two or more modular units and changing the single loop endless conveyor 14a to a convoluted endless conveyor 14 to service all of the modules. Endless conveyor 14 (FIGURES

2 and 3) is composed of three roller chains 15, 16, and 17 operated in unison, for instance by a common drive shaft 18 supported by bearings at one end of frame 12. Shaft 18 is driven by a controlled power source, such as motor 19, and transmission 20 mechanically coupled with the motor and shaft 18. Endless conveyor 14a is similarly constituted, although the configuration is somewhat different as discussed previously. Therefore, shaft 18a and transmission 20a respond in function to shaft 18 and transmission 20. Inasmuch as roller chains have been selected to exemplify a preferred type of conveyor, shafts and sprockets are necessary at the ends of each flight of conveyor 14.

The letter supporting structure, composed of a plurality of laterally spaced guides, forms a part of the machine to support letters L as they are propelled. The nature of the guides differs between adjacent superposed sections of the structure and the section which interconnects the superposed sections. For this construction, attention is directed to FIGURE 9 showing a first section 23, a second section 24, and an interconnecting section 25. Section 23 may have some gates 26 but has an entrance 91 (FIGURE 12) where there is no gate, while section 24 is entirely or almost entirely composed of a number of identical gates 26, each of which, when open, functions as a letter diverting means. The interconnecting section 25 is made of a number of laterally spaced plates 27, wires or the like formed with a curved outer surface 28. It is clearly evident that it is unnecessary for section 23 and/or section 24 to be made entirely of gates 26. Instead, one or more gates may be used, however, the more efficient arrangement is to have as many gates as possible in each of these sections.

Each gate is of open wire framework construction, e.g. made of wire, and is generally triangular when viewed from the side. The apex part 31 of the gate is slanted (FIGURE 9) to assure that a letter moving over the top of the gate will not slip between gates. If there is any tendency to slip between the adjacent gates, the leading edge of the letter rides on the inclined parts 31 of the gates and is smoothly guided along in its desired path of travel as shown by the arrows in FIGURE 9. Transverse brace 34, for instance a lightweight flat strip, is secured to the wire framework of each gate 26 for rigidity. Shaft 33 is fixed to gate 26 and extends through an opening 35 (FIGURE 8) in one of the frame members 12b of frame 12, and there is a gate operating cam mechanism 36 attached to one end of shaft 33. A device 38 is attached to the opposite end of shaft 33, for retaining the gate in the open or closed position. Device 38 is more fully described later, however, it functions like a toggle.

In addition to frame member 12b, there are parallel frame members 12c and 12d respectively for each module (FIGURE 2), and shaft 33 extends transversely across conveyor 14 which is supported by the three frame members 12b, 12c, and 12d for the upper flight of a single module of machine 10a or machine 10. The three frame members 12b, 12c, and 12d have longitudinal members 12e, 12f, and 12g on which resilient strips 40, 41, and 42 are secured. These resilient strips may be made of rubber or some other elastomeric substance. The roller chains 15, 16, and 17 are disposed on the strips so that the machine runs comparatively silently.

Laterally spaced guides 44 are attached to frame 12, and as shown in FIGURE 2, guides 44 are located above doors 26 of section 23 and for simplicity, they are shown as angle members. FIGURE 2 further shows that guides 44 are in echelon with doors 26. Guides 44 are similarly arranged with respect to section 24, although they are not shown in FIGURE 9 to simplify the drawing. Guides 46 of section 25 are connected to the adjacent ends of guides 44 of sections 23 and 24, but the curvature 47 is on a larger radius than the curvature of guides 25 and slightly eccentric thereto in order to have a larger throat

48 enabling the letters L to make the turn between sections 24 and 23.

The propulsion means for the letters are shown in FIGURE 10, and the relationship between the article supporting structure and the propulsion means is shown in FIGURE 2. The letter propulsion means are each composed of a symmetrical rod or rod-like member 50 which is of wavy or undulated shape to enable the member 50 to be interdigitated with guides 44, doors 26 and other parts of the letter supporting structure in the curved sections 25. The interdigititation is preserved as the propulsion means pass through connecting section 25 since the interconnecting section 25 was described as being made of a number of laterally spaced members 27. Guides 46 are also laterally spaced in the same fashion of the spacing shown in FIGURE 2. The relationship between member 50, gates 26, and guides 44 allows a given propulsion device 50 to move a letter throughout the entire path of travel of the machine regardless of the orientation of sections and regardless of the number of sections which are stacked or otherwise connected.

One end of member 50 is secured to conveyor chain 17, for example it may take the place of one of the pins of the roller conveyor. The opposite end 51 of the propulsion member 50 is passed through chain 16 of conveyor 14, secured to chain 15, and has a guide wheel 52 with a circumferential groove engaged with rail 53 that is secured to or constitutes a part of frame member 12b. Rail 53 is continuous and extends around each section of machine 10 regardless of the number of modules in the machine.

Mechanical code mechanism 56 is used in machines 10 and 10a, and the code mechanism is similar to the code mechanism shown and described in the previously referred to patent. Other code devices or mechanisms 35 may be adopted, however, the code mechanism illustrated and described in Patent No. 2,901,089 functions very well. Briefly, the code mechanism disclosed in that patent has an adjustable but stationarily supported code device 57 secured to a stationary part of the machine, and a movable code device 58 which is propelled in co-ordination with the movement of letter receptacles or pockets. We have modified the code mechanism 56 to some extent. Two swinging arms 59 and 60 have been mounted for pivotal movement on the end 51 of member 50. Code device 58 consisting of a number of code wheels 61 settable longitudinally on shaft 62, are carried by the arms 59 and 60 by having shaft 62 attached to these arms. Wheel 63 which rides on the surface of cam track 64 in a fashion quite similar to that described in the previously referred to patent, is mounted on shaft 62. Code bars 65 of device 57 are positionable at different places, and the code wheels 61 are adjustable on shaft 62 so that the machine may be coded or programmed. When the code devices 57 and 58 match, instead of having an arm drop vertically as in the previously referred to patent, the two arms 59 and 60 swing downward on the end 51 of propulsion device 50.

Swinging arm 60 has a cam follower 68, for example a wheel carried by a spindle 69 attached to arm 60. 60 The cam follower is used to actuate the gate operating mechanism 36 and for this construction reference to FIGURES 6-8 is suggested.

Gate operating mechanism 36 is made of a double cam 72 having two cams 70 and 71. The cams are spaced to define a throat 73 through which cam follower 68 passes. A stationary member, for example a plate 74, longitudinally divides throat 73 and the stationary member 74 is secured to frame member 12b. A supporting block 75 is secured to double cam 72 and has an opening 75 in it. Shaft or spindle 33 is fastened in this opening so that the shaft 33 is rotated clockwise or counterclockwise depending upon the direction of movement of the double cam 72. The two cam surfaces are relatively flat and tapered toward one another, and have divergent ends to permit the cam follower 68 to enter the double cam if the

conveyor belt is occasionally reversed during assembly or servicing.

FIGURE 7 shows the four possible operational conditions of gate operating mechanism 36. At the right side of FIGURE 7, cam follower 68 is shown entering the upper section of throat 73 which would mean that code mechanisms 57 and 58 are mismatched and wheels 63 did not drop into the dwell of the cam (FIGURE 6) but rather, were retained at the level 78 of the code bars 65, which is coincident with the top surface of cam 64. Cam follower 68 would then ride on member 74 and engage the surface of cam 70 and cause the double cam 72 to move mechanism 36 in the direction of the arrow. This moves typical gate 26 to a closed position.

The adjacent diagram (second from the right in FIGURE 7) shows the cam follower 68 entering the lower section of throat 73, meaning that shaft 62 was allowed to drop toward the cam dwell. This would be when the fixed and movable code devices 57 and 58 coincide. The result of cam follower 68 entering the lower section of throat 73 is that the gate operating mechanism is moved in the direction of the arrow and the gate connected to gate operating mechanism 36 is moved to an open position.

The next adjacent cam and cam follower relationship (second from left) merely shows that if the gate operating mechanism 36 is already in the position demanded by code mechanism 56, the cam follower 68 will simply pass through throat 73. The final condition (first from left) depicted in FIGURE 7 shows that cam follower 68 will pass freely through the upper section of the gate operating mechanism without disturbing the position, if the gate is already in the correctly closed position.

To the extent that the cam follower, code mechanism 56 and gate operating mechanism 36 coact to move the gate operating mechanism only when required, these may be considered as means for operating the gate only when the gate is not already in the desired position. Further, the gate does not continually cycle and recycle. Instead, it is actuated only upon demand and this reduces wear, vibration, and is mechanically simple. The gate 26 functions only on demand, and then only for a half cycle. FIGURE 5 shows one possible structural means for retaining the gate in the open or closed position, although other means which are more simple or more complex may be substituted. Shaft 33 has an arm 81 secured to one end and this arm constitutes a portion of means 38 briefly identified previously. Two adjustable mechanical stops, for example screws 82 and 83 are secured to frame member 12c and they establish the upper and lower limits of swinging movement of arm 81. Spring 84 is secured at its ends to frame member 12c and arm 81, and it operates like an overcenter toggle spring yieldingly retaining the arm 81 in the position to which it is moved by the gate operating mechanism 36. Other substitute expedients such as using the friction in the bearing for the gate 26, or having screws 82 and 83 magnetized as permanent magnets, may be used, however, it has been found that the illustrated spring means 38 serve the purpose very effectively and are quite simple in construction.

Each gate 26 has a letter pocket 88 below it in which the letters which are diverted by the gates, when open, are accumulated. The letter pockets may be similar to those in the previously referred to patent, in which case, they would be secured to the frame of the machine.

The method of loading the sorting machine forms no part of the present invention. It is sufficient to note (FIGURE 12) that guides 44 have a letter entrance opening 91, and an inserter schematically represented by gate 92, is registered with this opening. One or more openings 91 and inserters may be used. The inserter need be nothing more than a chute controlled by gate 92, but it is evident that machine 10 or machine 10a may be manually fed; use a conventional inserter or feed mechanism or a specially developed inserter.

In operation, letters L are inserted one by one so that a single letter enters the passageway between the letter supporting doors 26 and guides 44. Propulsion device 50 is used to move a single letter along the supporting structure. If the proper position for gate 26 at a given time and for a given letter is closed and the gate is already closed, the propulsion device 50 will simply move the letter over the gate as shown in FIGURES 4 and 9. When the letter being propelled by propulsion device 50 reaches a station at which the programming of the machine as established by a particular code mechanism 56, demands that the letter be dropped into a pocket or onto a transverse unloading conveyor, the particular gate in question is opened as shown in dotted lines at 26' in FIGURE 4, whereby the letter falls through the opening that is controlled by that gate. When a gate is open, the tip of the gate is above the plane of the adjacent letter supporting structure, and the member 50 continues to push the letter. The letter, therefore, must pass under the door.

Numerous modifications, variations, and changes of other types may be made in the light of the preceding disclosure. It is therefore to be understood that the illustrations are given by way of example only and that the invention may be practiced otherwise than specifically shown and described and still remain within the scope of the following claims.

We claim:

1. In a sorting machine which has an article supporting structure provided with openings to receive articles, a gate for each opening, each gate having a spindle, means connected with said spindle for turning said spindle to move the gate to the open and closed position respectively, resilient means retaining the gate in either position when moved thereto by said spindle turning means, movable means for propelling the articles on said structure and including an undulated member, mechanical coding means to govern the operation of said spindle turning means, said coding means including an arm swingably mounted on a part of said undulated member and swingable to a selected position as said spindle turning means are approached by said arm to engage said spindle turning means at a predetermined approach position, said spindle turning means including a pair of spaced cams connected with said spindle and providing a throat therebetween, and a cam follower on said arm which passes through said throat to move either cam when it is in the path of travel of said cam follower so that said cam follower passes through said throat without actuating either cam when neither cam is in the path of travel of said cam follower.
2. The machine of claim 1 wherein there is a stationary member between said cams longitudinally dividing said throat and providing a surface against which said cam follower reacts.
3. In an article sorting machine which has a plurality of gates providing a supporting surface for the articles, individual means for operating each gate including actuating means secured to each gate, article moving means to move the articles over said surface, a movable code device swingably connected to a part of said moving means, a stationary code device, and said movable code device being swingable to different positions representing code match and code mis-match respectively of said code devices and engaging said gate actuating means at one of said different positions, said gate actuating means including a movable member having a pair of spaced deflectors, said deflectors movable with said member, one of said deflectors being engaged to open a gate and the other being engaged to close the gate, and said deflectors providing clearance for said movable code device when the gate is already in the position called for by the code match or mis-match respectively.
4. In an article sorting machine having means to sup-

port the articles, a plurality of gates constituting a part of said article supporting means, a gate operating structure connected to each gate, an article moving means adjacent to said supporting means, a first code device adjacent to said support, a second code device movable with said article moving means and adapted to interrogate said first code device while being moved with said article moving means, said second code device including a shaft provided with a plurality of code elements, means mounting said shaft on a part of said article moving means to allow said shaft and elements to swing to a predetermined position when the codes of said code devices match, the swinging movement of said article moving means being with respect to said part of said article moving means, means connected with said shaft and engageable with said gate operating structure to actuate the same, said gate operating structure including means having spaced surfaces which define alternate passageways for said gate-operating structure actuating means, one passageway being entered when said code devices match and the other passageway being entered when the code devices mis-match, one of said passageways being in the closed position when the gate associated therewith is open and the other passageway associated with the same gate being in the open position when said gate is closed so that if said gate is already in the position called for by said gate-operating means actuating means the gate is not actuated by said gate-operating structure.

5. In an article sorting machine, a frame structure, a plurality of gates defining an article supporting surface, each gate having a spindle pivotally mounted on said frame structure, means including a plurality of spaced members to move individual articles along said surface in a predetermined path of travel, an escort code device connected with each member and movable in unison therewith, a second code device connected with said frame structure, there being a said second code device for each gate, each escort code device adapted to be preset in accordance with the destination information of the article which is moved by the said member with which the escort code device is associated and adapted to match the said second code device associated with the gate through which the last-mentioned article is supposed

to pass for sorting, said escort and second code devices having means enabling an escort code device to be displaced when an escort code device matches a said second code device, means for actuating said gates in the following mode: (a) when a gate is closed and a given pair of escort and second code devices match the gate is opened and remains open until the next succeeding escort code reaches the stationary code device of said given pair and (b) if said next escort code matches said stationary code said next escort code device is displaced and the open gate remains open but (c) if said next escort code device mismatches the stationary code the gate is closed, whereby a plurality of successive articles to the same destination pass through a gate which remains open until an article for another destination occurs at which the gate is closed, said gate actuating means including a cam mechanism for each spindle, each cam mechanism including a pair of spaced cam surfaces, a cam-operating member attached to each escort code device and being in one of two planes as a cam mechanism is approached, one plane being established when the escort and second code devices mismatch and the other plane established by the code devices matching at which said displacement of the escort code device occurs, so that one or the other of said cam surfaces can be engaged or passed by said cam-operating member when said member moves past said cam mechanism in either plane.

6. The sorting machine of claim 5 and resilient means operative to hold each gate in either the open or the closed position.

7. The sorting machine of claim 2 wherein the articles are letters which are adapted to move over said supporting structure while the articles are laying flat on said article supporting structure.
